UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

INTERMITTENT FEELER MECHANISM FOR LOOMS.

Application filed July 22, 1924. Serial No. 727,432.

To all whom it may concern:

Be it known that I, ALONZO E. RHOADES, a citizen of the United States, residing at Hopedale, in the county of Worcester and State of Massachusetts, have invented an Improvement in Intermittent Feeler Mechanisms for Looms, of which the following description, in connection with the accompanying drawings, is a specification, like characters on the drawings representing like parts.

This invention relates to feeler mechanisms for looms and more particularly to feeler mechanisms of the intermittent type wherein the feeler has periods of activity and periods of inactivity.

In weaving with some kinds of filling, it is found desirable to prevent the recurring contact of the feeler with the filling on detecting beats, and to this end the feeler is maintained for periods of inactivity in an inoperative position and is freed at intervals to its periods of activity. These periods of activity and inactivity may vary in length in accordance with the particular character of yarn being used in the shuttle.

One of the objects of the present invention is to provide a feeler mechanism of the intermittent type in which, during the periods of activity of the feeler, the feeler controller may be locked in its feeler freeing position and thus prevent it from interfering with the feeler action until the feeler has been moved frontwardly by a working supply of filling.

In accordance with the present invention, the feeler controller is operated from a train of mechanism at intervals, to cause the controller to move the feeler frontwardly to its inoperative position which is preferably beyond the reach of the filling on detecting beats, and when the feeler is to be freed for movement to its feeling position, the controller is operated to permit such movement of the feeler, and when in its feeler releasing position is locked until on a detecting beat the feeler is moved frontwardly by a working supply of filling. Thus the lock prevents the actuation of the feeler controller during the activity of the feeler until the latter shall have performed one or more of its feeling functions.

The novel features of the invention and new combination of parts will best be made clear from the following description and the

accompanying drawings of one good practical form of the invention.

In the drawings:

Fig. 1 is a perspective view at the feeler side of the loom with the present invention associated therewith;

Fig. 2 is a detail of the controller actuator and associated parts;

Fig. 3 shows the feeler mechanism on an enlarged scale with the feeler held in its frontward inoperative position;

Fig. 4 is a side elevation of the feeler mechanism of the present invention, showing the feeler controller locked in its feeler freeing position and about to be tripped by the frontward movement of the feeler; and

Fig. 5 is a view similar to that of Fig. 4 showing the controller as having been tripped from the lock and moved frontwardly to withdraw the feeler into its inoperative position.

In the feeler mechanism shown by the drawings, the feeler is illustrated as of the inclined type in connection with which the advantages of the present invention are manifested, but it is to be understood, of course, that the invention may be utilized advantageously with other types of feelers.

It has not been deemed necessary to show the filling replenishing mechanism whereby the new supply of filling is furnished the loom, because the details of such mechanism form no part of the present invention and are now well understood in the art.

The loom frame 1 having the usual breast beam 2 is provided with bearings 3 for the transverse or rock shaft 4 for controlling the replenishing mechanism, as usual, and rising from the rock shaft 4 is an arm 5 pivotally connected at 6 to the rearwardly extending arm 7 to which is pivoted at 8 an end portion 9 adapted to be engaged at times by an operating member 10 which in the present instance is shown as the cam follower or a part connected thereto.

Underlying the finger 11 secured to the member 9 is an arm 12 of a bell crank lever pivoted at 13 on a support 14 mounted on the loom frame, and connected to the other arm 15 of the bell crank lever is a transmitter 16 through which the feeler acts to effect replenishment of filling when that in the shuttle is substantially exhausted on a detecting beat.

5 Adjustably mounted on the loom frame is the feeler stand 17 which may be appropriately secured to an adjustable bracket 18 carried on the shipper stand by means of a bolt or other securing means 19.

10 At the rear of the feeler stand is a guide-way extending laterally thereof for the guidance of a slide 20 through which the feeler 21 extends. The slide 20 is provided with an opening for the passage of the feeler 21, and interposed between a collar or bridge piece 22 secured to the feeler and a swivel block 23, at the front of the feeler stand through which the frontwardly extending stem 24 of the feeler extends, is a spring 25 which normally tends to move the feeler rearwardly to feeling position.

20 The parts so far described are similar to the corresponding parts more fully elucidated in the patent to Edward S. Stimpson, No. 1,309,226, July 8, 1919, but the feeler and its train of mechanism for effecting replenishment of filling may be of other types.

25 The lay 26 has the usual shuttle box 27, the front wall of which has an opening 28 which registers with a similar opening 29 in the shuttle 30 when the latter is in the feeler box. In this respect also the construction may be substantially the same as 30 in the Stimpson patent above mentioned.

35 The feeler stand may be appropriately provided with a bracket 31 and is shown as adjustably connected to the front portion of the feeler stand by a bolt 32. Extending downwardly from the bracket 31 is an arm 33 on which is mounted a bell crank lever 34. As shown, the bell crank lever is mounted to rock upon the stud 35 carried by the bracket 33 and an upwardly extending arm 36 of the bell crank lever is pivotally connected at 37 to a feeler controller 38 which is mounted for movement towards and from the front of the loom.

40 In the present instance, the controller 38 is provided with a slot 39 which travels on a pin or stud 40 projecting from the feeler stand 17. The slot 39 is curved in order to preserve a substantially rectilinear movement of the controller 38 towards and from 45 the front of the loom in response to movement of the bell crank lever, but it is apparent that the connection between the bell crank lever and the controller may be so contrived as to impart to the feeler controller its prescribed movements by other forms of guiding means.

50 The feeler controller 38 has a shoulder or tooth 41 at its rear end which is adapted to engage a part carried by the feeler and therethrough to move the feeler frontwardly when the controller 38 is so moved. As shown, the shoulder or tooth 41 is adapted to engage a stud projection 42 extending from the feeler or the collar 22 which is 55 secured to the feeler.

70 The controller 38 is provided with a locking tooth or projection 43 which is located frontwardly of the loom relative to the shoulder or tooth 41, and which is adapted to be engaged by the locking device when the feeler 38 is moved to its rearward position to permit the feeler to assume its feeling function.

75 The particular form of locking device shown consists of a pawl or arm 44 pivotally mounted at 45 on an upwardly extending arm 46 on the bracket 31, and a spring 47 normally acts to assist gravity in moving the locking device 44 to its locking position in engagement with the tooth or shoulder 43 extending from the controller. The locking device 44 is provided with a shoulder 44* which engages the shoulder or projection 43 on the feeler controller to lock it in its rearward position.

80 In accordance with the present invention, the feeler controller 38 is to be locked in its rearward or feeler freeing position during a period of activity of the feeler and is to continue to be locked in said position until the feeler itself meets a working supply of filling in the shuttle on a detecting beat and is moved frontwardly thereby. When the feeler is moved frontwardly by a working supply of filling, the present invention contemplates that the locking device 44 shall be tripped from locking engagement with the controller so that the latter may be moved frontwardly by its actuating mechanism to withdraw the feeler frontwardly 85 into its inoperative position and preferably beyond the reach of the filling on detecting beats.

85 A convenient form of trip, as shown in the present instance, consists of an inclined 105 surface 48 formed on the end portion of the locking device 44, which is adapted to be engaged by the projection 42 carried by the feeler, when the latter is moved frontwardly 110 by a working supply of filling on a detecting beat.

90 The arm 34 of the bell crank lever is connected at 49 to a rod 50 extending upwardly, in the present instance, from an arm 51 115 preferably mounted at 52, Fig. 1, on a bracket 53 which may be appropriately secured to the loom frame as by a bolt 54, Fig. 2. The arm 52 is normally under the influence of a spring 55, one end of which is connected to a bracket arm 56 and the other end of which is connected to the arm 51 at 57, the construction being such that the impulse of the spring 55 normally tends to move the arm 51 contraclockwise, as shown, and such movement is limited by a stop 58 which may be appropriately secured to the bracket 53.

95 In accordance with the present invention, the arm 51 is to be actuated at intervals to 120 operate through the feeler controller and 125

permit the feeler to move to feeling position, and is subsequently returned to its normal position under the influence of the spring 55 to move the controller frontwardly and 5 withdraw the feeler from feeling position.

The actuator for thus periodically operating the arm 51 may be variously contrived from a going part of the loom but in the present instance of the invention the actuator is 10 formed as a lug 59 projecting from the face of a worm wheel 60 mounted on a stud 61 and operated by a worm 62 on the shaft 63 which is shown as extending frontwardly and is operated by a train of gearing from 15 the under or cam shaft of the loom.

The shaft 63 may be connected to the take-up mechanism as usual in some types of looms, for operating the train of take-up gearing 64 and 65 for taking up the cloth 20 as it is woven. From the construction described it will be clear that when the controller 38 is in its frontward position to which it is moved by the spring 55, the shoulder or tooth 41 of the controller will 25 engage the projection 42 of the feeler and hold the latter in its frontward inoperative position. When the actuator 59 of the gear 60 or other rotating part engages the end 66 of the arm or lever 51, it will turn the latter 30 clockwise, as shown, thereby turning the bell crank lever and moving the controller 38 rearwardly to thereby permit the feeler to move to feeling position, and as soon as the actuator 59 has passed the end 66 of the 35 lever 51, the spring 55 will tend to restore the parts to their previous position. When, however, the controller 38 has been thus moved to its rearward position, it is engaged by the locking device 44 to maintain it in its 40 rearward feeler freeing position, notwithstanding the action of the spring 55. The feeler being now in feeling position may meet a working supply of filling on a detecting beat, whereupon the feeler will be 45 moved frontwardly and, acting through the trip 48, will lift the locking device 44 and free the controller 38 to movement frontwardly responsive to the spring 55, and as the controller moves frontwardly, under the 50 conditions described, the tooth or shoulder 41 of the controller will engage the feeler projection 42 and move the feeler frontwardly to its inoperative position beyond the reach of the filling on subsequent detecting beats. Should, however, the feeler find a near approach to substantial exhaustion of the filling during its active period, it will 55 not be moved frontwardly sufficiently far to act upon the trip 48 to free the controller, but will remain in active operation and call for replenishment of filling when that in the shuttle is substantially exhausted, the feeler controller at such times being locked in its feeler freeing position. When a fresh 60 supply of filling has been furnished, the 65

feeler will be moved frontwardly on the following detecting beat and again act to unlock or free the controller to its movement frontwardly and thereby again cause movement of the feeler to its frontward inoperative position. 70

What is claimed is:

1. In an intermittent feeler mechanism for looms, the combination of a feeler having periods of activity and inactivity during weaving with the same supply of filling in the shuttle, means for moving the feeler from active position and operating at intervals to permit the feeler to move to active position, and a lock for preventing the said 80 means from moving the feeler to its inactive position until the lock is tripped as the feeler is moved frontwardly by a working supply of filling. 85

2. In an intermittent feeler mechanism for looms, the combination of a feeler, a feeler controller for determining the active and inactive periods of the feeler, means for operating the controller at intervals, and a lock for holding the controller in its feeler 90 freeing position during activity of the feeler until the feeler is moved frontwardly by a working supply of filling. 95

3. In an intermittent feeler mechanism for looms, the combination of a feeler, a feeler controller for determining the active and inactive periods of the feeler, means for operating the controller at intervals, and a lock for holding the controller in its feeler 100 freeing position during a period of activity of the feeler until the feeler is moved frontwardly by a working supply of filling and thereby causes the lock to be tripped. 105

4. In an intermittent feeler mechanism for looms, the combination of a feeler, a feeler controller for determining the active and inactive periods of the feeler, means for operating the controller at intervals, a lock for holding the controller in its feeler freeing position during activity of the feeler, 110 and means for tripping the controller lock when the feeler is moved frontwardly by a working supply of filling. 115

5. In an intermittent feeler mechanism for looms, the combination of a feeler, a feeler controller for determining the active and inactive periods of the feeler, means for operating the controller at intervals that the feeler may have periods of activity and periods of inactivity, a lock for holding the controller in feeler freeing position, and means actuated by the feeler when it is moved frontwardly by a working supply of filling for freeing the controller from the lock that the controller may cause the feeler to be 120 held in its inactive position. 125

6. In an intermittent feeler mechanism for looms, the combination of a feeler, a feeler controller movable to one position for withdrawing the feeler from feeling position 130

4

and movable to another position that the feeler may move to feeling position, means for operating the controller, a lock for locking the controller in its feeler freeing position, and feeler actuated means for tripping the lock when the feeler is moved frontwardly by a working supply of filling on a detecting beat.

7. In a feeler mechanism for looms, the combination of a feeler, a feeler controller movable towards the front of the loom for withdrawing the feeler from feeling position and movable towards the rear of the loom to permit the feeler to move to feeling position, means for operating the controller, and a controller lock for preventing frontward movement of the controller responsive to said means during an active period of the feeler until the latter is moved frontwardly by a working supply of filling on a detecting beat.

8. In a feeler mechanism for looms, the combination of a feeler, a feeler controller movable towards the front of the loom for withdrawing the feeler from feeling position and movable towards the rear of the loom to permit the feeler to move to feeling position, means for operating the controller, a controller lock for preventing frontward movement of the controller responsive to said means during an active period of the feeler until the latter is moved frontwardly by a working supply of filling on a detecting beat, and a trip actuated by the feeler.

9. In a feeler mechanism for looms, the combination of a feeler, a sliding controller for determining the active and inactive periods of the feeler, means for operating the

controller at intervals, a controller lock for holding the controller in feeler freeing position, and a trip actuated by the feeler when it is moved frontwardly by a working supply of filling on a detecting beat that the controller may act in response to its operating means to withdraw the feeler from feeling position.

10. In a feeler mechanism for looms, the combination of a feeler, a feeler controller movable towards and from the front of the loom to determine the active and inactive periods of the feeler, a projection connected to the controller, a lock for engaging said projection when the controller is in feeler freeing position, and a feeler actuated trip for freeing the controller from the lock that the controller may move the feeler to a position beyond the reach of the filling on subsequent detecting beats.

11. In an intermittent feeler mechanism for looms, the combination of a feeler, a feeler controller for determining the active and inactive periods of the feeler, an arm connected to the controller, an actuator for said arm for permitting the feeler to move to feeling position at intervals, a spring acting through the controller for placing the feeler in an inoperative position during its periods of inactivity, and a controller lock for preventing movement of the controller responsive to said spring until the lock is tripped on a detecting beat by a working supply of filling in the shuttle.

In testimony whereof, I have signed my name to this specification.

ALONZO E. RHOADES.
